UNITED STATES PATENT OFFICE

109,612

DESIGN FOR A TOY FIGURE

Elizabeth S. Dutcher, Sunnyside, Long Island,
N. Y.

Application September 29, 1937, Serial No. 71,865

Term of patent 7 years

To all whom it may concern:

Be it known that I, Elizabeth S. Dutcher, a citizen of the United States, residing at Sunnyside, Long Island, in the county of Queens and State of New York, have invented a new, original, and ornamental Design for a Toy Figure, of which the following is a specification, reference being made to the accompanying drawing, forming part thereof.

I claim:

The ornamental design for a toy figure as shown.

ELIZABETH S. DUTCHER.
